Primary Examiner — T Chase Nelson*Assistant Examiner* — Kelly L Gross(74) *Attorney, Agent, or Firm* — Gulf Coast Intellectual Property Group(57) **CLAIM**

The ornamental design for the cannulation splint as shown and described.

DESCRIPTION

FIG. 1 is a perspective view of the cannulation splint of present invention; and

FIG. 2 is a rear view thereof; and

FIG. 3 is a front view thereof; and

FIG. 4 is a left side view thereof; and

FIG. 5 is right side view thereof; and

FIG. 6 is a bottom view thereof; and,

FIG. 7 is a top view thereof.
